UNITED STATES PATENT OFFICE.

JOHN O'CALLAHAN, OF PHILADELPHIA, PENNSYLVANIA.

DESIGN FOR A BADGE.

SPECIFICATION forming part of Design No. 23,463, dated July 17, 1894.

Application filed April 23, 1894. Serial No. 508,739. Term of patent 7 years.

To all whom it may concern:

Be it known that I, JOHN O'CALLAHAN, a citizen of the United States, and a resident of the city of Philadelphia and State of Pennsylvania, have invented a certain new and original Design for Badges, of which the following is a full, clear, and exact description, reference being had to the accompanying drawing, forming part of this specification.

10 My design for a funeral badge is fully shown in the accompanying drawing.

At the central upper portion of the badge is a representation of two waving flags, *a*, the staffs, *b*, of which are crossed and at the crossing point are united by a bow of ribbon, *c*, as shown. Below the flags is a representation of a cross, *d*, from the center of which extend radiating lines representing rays of light and

across the lower portion of the cross extends a scroll, *d'*. Below the cross and scroll is an ornamental figure, the opposite sides of the lower portion of which are curved to represent scrolls, *e*, while its upper face is on a curved line, at the opposite ends of which are ornamental edge borders, *f*. The base portion of this figure is formed by a series of curved and waved lines, *g*.

I claim as my invention—

The design for a badge substantially as herein illustrated and described. 30

In witness whereof I have hereunto set my hand this 13th day of April, A. D. 1894.

JOHN O'CALLAHAN.
